UNITED STATES PATENT OFFICE

ERICK SILEN, OF STELLA, WASHINGTON

POWER GUIDE ROLLER

Application filed September 3, 1930. Serial No. 479,543.

This invention relates to rollers designed for use as guides over which fish nets are moved in hauling the nets.

The primary object of the invention is to provide a roller of this type so constructed that it may be power operated, thereby to assist the operators in lifting and hauling heavy nets, as they are being pulled into the vessel.

10 Another object of the invention is the provision of means in the form of a foot lever, for throwing the power mechanism into and out of operation, at the will of the operator.

Still another object of the invention is to provide a device of this character which may be readily and easily installed, without the necessity of making extensive alterations in the construction of the vessel in which the power mechanism is installed.

20 With the foregoing and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

25 Referring to the drawings:

Figure 1 is an elevational view illustrating a power guide roller constructed in accordance with the invention, together with the operating mechanism therefor.

30 Figure 2 is a sectional view taken on line 2-2 of Figure 1.

Figure 3 is a sectional view taken on line 3-3 of Figure 1.

35 Figure 4 is a plan view of the operating mechanism, the power guide roller being shown in section.

Figure 5 is a detail view illustrating the manner of connecting the power disk to the fly wheel of the motor of the operating mechanism.

40 Figure 6 is an enlarged sectional view illustrating the manner of mounting the power roller.

45 Referring to the drawings in detail, the reference character 5 designates the side of a

vessel which is equipped with a roller constructed in accordance with the invention.

The reference character 6 designates the roller base which is secured to the deck of the ship to prevent lateral movement thereof, 55 by means of the pin 7 which passes through the base and deck 8. The base 6 and deck, are formed with openings to receive the pin 9 which is substantially long and extends through the deck 8, the pin being so constructed that no nut is necessary to secure the same in position, thereby providing means for securing the roller to the deck of the ship in such a way that the roller may be readily lifted from its position, when not in 60 use.

Arms 10 extend upwardly from the base and are provided with bearings to receive the shaft 11 of the guide roller 12.

Extending forwardly from the base 6, is an extension 13 that provides a support for the lower end of the roller 14, the upper end of the roller 14 being held in position by the upper end of the arm 10 at one end of the roller 12.

70 The reference character 15 designates a pivoted arm which extends under the roller, the free end of the arm providing a support for the vertical guide roller 16. A shaft 17 provides the pivot for the arm 15, the shaft being square and fitted in a square opening of the arm 15 to move the arm when the shaft is rotated.

75 Lever 18' is mounted on the lower end of the shaft 17 and connects with the rod 32 to operate the shaft and lever 18' when the rod is moved. Coiled spring 19' is connected with the arm 15 at one end of the spring, the opposite end of the spring being secured to the deck at '20', to return the arm to its normal inactive position after it has been operated.

80 As clearly shown by Figure 3 of the drawings, the roller 12 embodies heads 18 fitted in the ends of the body portion of the roller, which body portion is formed of sheet metal material having its periphery corrugated to present a roughened surface so that the net operating over the roller, will be gripped by the roller and moved therewith.

On one end of the shaft 11, is a pinion 19 that is in mesh with the pinion 20 carried at the upper end of the shaft 21, which shaft is clutched to the shaft 22, by means of the clutch member 23. This clutch member 23 includes a stationary section and a movable section, the movable section being operated by means of the arm 24 which is pivotally mounted at one end of the support 25. One end of the arm 24 is forked to fit within the collar 26 of the movable clutch section.

Mounted on the platform 27, is a treadle 28 to which the link 29 is connected, the link 29 being also connected with the arm 24 at 13 30. After the treadle 28 has been forced downwardly to operate the clutch, the treadle is returned to its normal position by means of the coiled spring 19' which has connection with one end of the rod 32 that in turn 20 is connected with the bell crank lever 33.

A link 34 connects the bell crank lever to the treadle 28, so that movement of the spring and rod 32 will pull the treadle upwardly to its inactive or normal position.

25 A pinion 35 is secured to the lower end of the shaft 22 and is in mesh with the pinion 36 secured to the shaft 37, which shaft 37 is mounted in bearings 38 and 39. Mounted on one end of the shaft 37 is a sprocket 40 over 30 which the chain 41 operates, the chain also operating over the sprocket 42, to receive rotary motion therefrom. Secured to the hub of the sprocket 42 is an arm 43 that carries a counterbalancing weight 43' at one end 35 thereof, the opposite end of the arm 43 providing a support for the finger 44 which is normally held in its active position by means of the coiled spring 45. This finger 44 cooperates with the extension 45' that extends 40 from the periphery of the power disk 46, the extension 45' contacting with the finger 44 to rotate the arm 43 and sprocket 42 to which the arm is connected.

The power disk 46 is secured to the spokes 45 of the fly wheel 47 by means of the securing bolts 48, the fly wheel forming a part of the power device 49.

From the foregoing it will be obvious 50 that due to the construction shown and described, I have provided a power guide roller so constructed that it may be readily thrown into and out of operation by the operator merely placing his foot on the treadle 28, to the end that the power guide roller will be 55 rotated to permit the fish net to be hauled with facility.

I claim:

1. In a power guide roller, a base, a roller member mounted on the base, vertical rollers disposed laterally of the roller member, a pivoted arm for supporting one of the vertical rollers to move the vertical roller supported thereby towards the vertical roller at 60 the opposite end of the roller member, and

means for throwing the roller member into and out of operation.

2. In a power guide roller, a base, a guide roller mounted on the base, vertical rolls disposed at the ends of the guide roller, means for supporting one of said vertical rollers for lateral adjustment with respect to the guide roller, and means for operating the guide roller.

In testimony that I claim the foregoing as 75 my own, I have hereto affixed my signature.

ERICK SILEN.
